Inventor
Kine Gross,
By Clarence A. O'Brien
Attorney

UNITED STATES PATENT OFFICE.

KINE GROSS, OF WELLMAN, IOWA.

REFRIGERATOR.

Application filed September 11, 1922. Serial No. 587,378.

To all whom it may concern:

Be it known that I, KINE GROSS, a citizen of the United States, residing at Wellman, in the county of Washington and State of 5 Iowa, have invented new and useful Improvements in Refrigerators, of which the following is a specification.

The object of my said invention is the provision of a refrigerator which is, at once, 10 simple and inexpensive in construction and highly efficient in on-heat-conducting capacity, whereby it is adapted with or without the assistance of ice to preserve its contents in a wholesome state for an indefinite period 15 of time.

To the attainment of the foregoing, the invention consists in the improvement as hereinafter described and definitely claimed.

In the accompanying drawings, forming 20 part of this specification:—

Figure 1 is a side elevation, partly in section, of a refrigerator constructed in accordance with my invention.

Figure 2 is a vertical diametrical section 25 of the same.

Figure 3 is a horizontal section taken in the plane indicated by the line 3—3 of Figure 1.

Figure 4 is a detail vertical section taken 30 on the line 4—4 of Figure 1.

Figures 5 and 6 are detail views of a modified door construction hereinafter explicitly referred to.

Similar numerals designate correspond- 35 ing parts in Figures 1 to 4 to which reference will first be made.

Among other elements my novel refrigerator comprises a casing body 1, preferably of general cylindrical form and made of 40 galvanized iron or other appropriate metal. At its upper end the said casing body 1 is provided with an inwardly directed flange 2. The inner side of the casing body 1 is lined with quicksilver, as designated by 3, 45 Figure 2, with a view to increasing its ability in preventing the passage of heat.

Within the metallic casing body or jacket 1 and snugly fitting the same is a comparatively thick lining 5 of hard material con- 50 ductive in character and susceptible of being easily cleaned, such as glass, porcelain, arti- ficial stone, vitrified earthenware, granite or equivalent material. The said lining is provided at its upper end with an inwardly- 55 reaching annular flange 5 which is of a greater width than the flange 2 in about

the proportion illustrated. At intervals in its height the lining 4 is provided with interior lugs 6 to support appropriate shelves 7, and with upper interior lugs 8 to support 60 an annular pan 9 from which a drain pipe 10 extends downwardly to an aperture 11 in the side wall of the refrigerator body and outwardly through the aperture, a gasket 12 or appropriate packing being em- 65 ployed in the aperture and about the pipe to prevent the passage of air. Spaced above the pan 9 is a platform 13 for ice, when ice is to be used in the refrigerator, the said platform being supported by legs 14 which 70 are superimposed on the bottom of the pan so as to permit the free passage of cold air downwardly from the ice.

Door openings 15 are provided in the body of the refrigerator, Figure 1, and arcuate sliding doors 16 are employed to normally close said openings; the doors being constructed in the same manner as the refrigerator body, Figure 4, for non-heat- 75 conducting purposes, and the joints be- 80 tween the doors and the refrigerator body being broken to form an air lock as design- 85 ated by 17. I would also have it under- 90 stood at this point that the lining 4 is re- cessed at its inner side, as designated by 18 in Figure 3, in order to accommodate the doors when opened, and that the upper and lower walls of the said recesses 18 are grooved as indicated by 19 to receive and guide the tongues on the doors. At 20 are 95 handles on the doors.

The upper end of the lining 4 is closed by a cover 21 of the same material as the lining, the said cover being threaded and removably secured in the flange 5, as design- 95 ated by 22, and being equipped with an appropriate handle 23.

Enclosing the upper end of the refrigerator body is a cap 24 removably arranged over said end and formed by preference of 100 metal and preferably lined with quicksilver as designated by 25.

I prefer in practice to employ the doors 16 constructed and arranged in the manner shown and described. I do not desire, how- 105 ever, to be limited to said doors inasmuch as it is within the purview of my invention as defined by some of my claims to employ threaded doors 16^x such as shown in Figures 5 and 6 or doors of any other suitable description.

It will be apparent from the foregoing

that my novel refrigerator notwithstanding its practical advantages is simple and inexpensive in construction and is susceptible of being manufactured with facility.

5 I have entered into a detailed description of the construction and relative arrangement of the parts embraced in the present and preferred embodiments of my invention in order to impart a full, clear and exact 10 understanding of the said embodiments. I do not desire, however, to be understood as confining myself to the specific construction and relative arrangement of parts inasmuch as in the future practice of the invention various changes and modifications 15 may be made such as fall within the scope of my invention as defined in my appended claim.

Having described my invention, what I claim and desire to secure by Letters Patent, is:—

A refrigerator comprising a metallic casing body, a lining of hard material substantially as specified snugly fitting within the casing body, and a lining of quicksilver at 25 the inner side of the casing body and between the same and the first-named lining; the casing body and the first-named lining having inwardly-directed flanges at their upper ends, a cover of the same material as the first-named lining threaded into the flange of the same, and a metallic cap removably arranged over the refrigerator body.

In testimony whereof, I affix my signature.
KINE GROSS.
